CAR POSTER PANEL

Filed Sept. 4, 1928

UNITED STATES PATENT OFFICE

JULIUS C. BANDINI, OF FLUSHING, NEW YORK

CAR POSTER PANEL

Application filed September 4, 1928. Serial No. 303,913.

My invention is an improvement in poster panels of that particular class which are employed in connection with car advertising and in which the advertising cards or posters are contained in a longitudinal frame or panel extending along the inner side of the car above the windows where the sides of the car adjoin the ceiling.

The primary object of my invention is to provide a car poster panel or frame for advertising cards of this general character in which a larger number of advertising cards or posters may be contained in the panel and successively brought in position or exposed to the view of the passengers, not only to change the advertising matter with respect to different advertisers but also make it possible to change the form of the card or advertising matter of each of several individual advertisers.

A further object of my invention is to provide a frame or car poster panel for advertising cards in which the changes for the purposes above mentioned may be made quickly and conveniently without handling the cards, in the present instance moving them by a mechanical means from unexposed to exposed position, and vice versa.

With these principal objects in view my invention consists in providing a poster card frame or car panel in which the cards are arranged one back of another and connected to an endless chain by means of which the cards are moved from front or exposed position to rear or unexposed position back of the front cards by the simple operation of the endless chain; all as hereinafter fully described and specifically set forth in the appended claims.

In the drawings:

Figure 1 is a front elevation of a car poster panel constructed in accordance with my invention.

Fig. 2 is a detailed view in front elevation of one of the card carriers.

Fig. 3 is a similar view showing an advertising card or poster in connection with the carrier.

Fig. 4 is a sectional view on the line 4—4 of Fig. 3.

Fig. 5 is a detailed perspective view of the upper rail of the poster panel.

Fig. 6 is a sectional view on the line 6—6 of Fig. 5.

Fig. 7 is a detailed perspective view of the lower rail of the poster panel; and

Fig. 8 is a sectional view of Fig. 7 through the axis of the sprocket wheel.

In carrying out my invention I provide an upper rail 10 and a lower rail 11 between which the advertising cards are mounted, said rails each having attaching means, as metal straps 12 and 13 respectively, for securing them at the upper and lower edges of the longitudinal panel usually provided in cars at the juncture of the sides with the ceiling, and in the present instance each rail is provided with two channels or trackways 14 14 and 15 15 to receive the upper and lower edges of the advertising cards 16 or plates 17 carrying the same, the said cards and plates being curved transversely as shown in Figures 2 and 3 to correspond with the curved panel of the car and the two sets of channels or trackways permit the cards to be mounted in the poster panel one behind another. In order that the cards, or plates which carry the same, may be inserted into position between the rails at any part of the poster panel the upper rail consists of three spaced apart metal strips 18, 19, and 20 so that the channels or trackways 14 14 open out at the upper as well as the lower part of the rail, and for holding said strips in proper spaced relation the metal straps 12 are attached, by welding or otherwise, to the front and rear strips 18 and 20, with the intermediate strip 19 attached at its upper edge to said straps, the latter having an extension 21 by which it is secured to the car panel. In addition to the attaching straps 12 12 the aforesaid plates forming the trackways of the upper rail are connected together by narrow plates 22, for the special purpose of holding in place strips 23 of less depth than the intermediate strips 19 on a line therewith whereby a card or poster may be moved from alignment with one channel to another, for the purpose hereinafter explained, said narrow intermediate strip 23 being located at each end of the poster

100

panel although in the drawings it is shown at one end only, as part of the poster panel or other end thereof is broken away. The channels or trackways in the lower rail 11 are formed by the front and rear walls 24 and 25 in connection with an intermediate wall 26, in this instance the several walls being connected at their lower ends by a cross-piece 27 forming the bottom of the rail and trackways therein.

The plate 17 which carries the advertising card 16 is rectangular in shape and of a width to fit between the rails 10 and 11 of the poster panel to engage in the trackways in said rails, the upper and lower edges 28 and 29 of said plate being turned over to provide retaining flanges for the opposite edges of the card, and at one end of said plate are retaining flanges 30 to receive the corresponding edge of the advertising card or poster so as to cooperate with the aforesaid turned over edges 28 and 29 in retaining said advertising card or poster in intimate connection with the plate. To provide for shifting the upper ends of the cards from one channel or trackway to another, as for instance from the front trackway to the rear trackway, the plate is provided at its upper corners with tongues 31, and as the cards are shifted only at the ends of the poster panel I provide at the opposite ends of the narrow intermediate strip 23 spring fingers 32 which engage the tongues 31 and push the upper end of the card from the front channel to the rear channel under the aforesaid narrow strip as the said card is moved from one position to another or from right to left in Fig. 1, said spring fingers or guiding members 32 cooperating with an endless chain 33 mounted in the lower rail on a sprocket wheel 36 at each end of the poster panel, with the two lengths thereof traveling in opposite directions in the channels, or to the left in the front channel and to the right in the rear channel, the advertising cards or posters being connected to the chain by pins 34 projecting from the lower edge of the plates 17 carrying said advertising card to engage in apertures 35 therefor in the links of the chain, as shown in Figs. 7 and 8. It will be understood that the advertising cards in the front channel of the lower rail are moved to the left and the cards in the rear channel to the right behind those in front, and that the arrangement hereinbefore described for shifting one of said cards from the front channel to the rear channel is duplicated at the other end of the poster panel but in reverse order to shift an advertising card or poster from the rear channel to the front channel, whereby at one end of the poster panel, (the left end as shown in Fig. 1) the cards are shifted in succession from front or exposed position to rear or unexposed position and at the other end of said poster panel from unexposed to exposed

position, and it will be noted by reference to Fig. 7 that the intermediate wall 26 is cut away at the end of the poster panel where the cards are shifted from one channel to another or below the narrow strip or rail 23 between the channels 14 of rail 10 in which the upper ends of the cards travel. The sprocket wheel 36 is turned by means of a rod 37 depending therefrom, which of course may be provided with a crank-handle (not shown) and with ratchet and pawl (not shown) as usually provided in connection with an endless chain or web such as provided for sign exhibitors.

The purposes and operation of my improved poster panel will be readily understood from the foregoing description in connection with the accompanying drawings, for it provides a simple and effective arrangement especially adapted for car poster panels by which an additional set of advertising cards are mounted in the panel so that they may be successively brought into exposed position or display with those in the rear reserved for future display, in other words providing for changing the advertisements on display as desired, and, as hereinbefore stated the cards may be advertisements of different concerns or a variety of advertisements of one or more concerns. The advertising cards of posters may be readily inserted in the poster panel at any part thereof by simply passing the upper end of the card into one of the channels 14 of the upper rail and then dropping it into one of the channels 15 of the lower rail to engage the pin 34 of plate 17 carrying said card into one of the apertures 35 in the chain 33.

It will of course be understood that the construction and arrangement herein shown and described is the preferred embodiment of my invention, and that the same is susceptible of modifications or changes within the spirit and scope of the appended claims to attain the purposes specifically set forth.

I claim:

1. A car poster panel comprising upper and lower rails presenting trackways for sets of advertising cards positioned one behind another, and an endless chain engaging the cards at the center thereof to move them successively from one channel to the other at the opposite ends of the car poster panel.

2. A car poster panel comprising upper and lower rails presenting trackways for sets of advertising cards traveling in said trackways, an endless chain traveling in opposite directions in the trackways and having apertures in the links thereof, and a pin projecting from the center of the advertising cards into engagement with apertures in the links of the chain.

3. A car poster panel comprising upper and lower rails presenting trackways for sets of advertising cards traveling in said track-

- ways, said trackways communicating one with the other at opposite ends of the poster panel, an endless chain traveling in opposite directions in the trackways of one of the 5 rails and having apertures in the links thereof, and a pin projecting from the center of each advertising card to engage one of the aforesaid apertures in the endless chain.
4. A car poster panel comprising upper 10 and lower rails presenting trackways, the upper rail consisting of spaced apart strips connected at their upper ends with the intermediate strip reduced in width at the opposite ends of the poster panel and the lower 15 rail consisting of outer and inner walls with an intermediate wall, the latter being cut away below the aforesaid narrow portions of the intermediate strip of the upper rail, an endless chain traveling in opposite directions in the trackways of one of the rails and 20 having apertures in the links thereof, and a pin projecting from the center of the advertising card into engagement with apertures in the links of the chain.
- 25 5. A car poster panel comprising upper and lower rails presenting trackways, the upper rail consisting of spaced apart strips connected at their upper ends with the intermediate strip reduced in width at the opposite 30 ends of the poster panel and the lower rail consisting of outer and inner walls with an intermediate wall, the latter being cut away below the aforesaid narrow portions of the intermediate strip of the upper rail, and 35 an endless chain traveling in opposite directions in the trackway of one of the rails and having apertures in the links thereof; together with a plate in which the advertising card is mounted, and a pin projecting from 40 the plate to engage one of the aforesaid apertures in the endless chain.
6. A car poster panel comprising upper and lower rails between which the advertising cards or posters are mounted, and an endless chain traveling in one of said rails horizontally in opposite directions; together with a frame or plate in which the advertising card is mounted, and a pin projecting from the center of the plate and engaging the endless 50 chain.
7. A car poster panel comprising upper and lower rails presenting trackways, the upper rail consisting of spaced apart strips connected at their upper ends with the intermediate strip reduced in width at the opposite 55 ends of the poster panel and the lower rail consisting of parallel walls with the intermediate wall cut away below the aforesaid narrow portions of the intermediate strip of the upper rail, and guiding fingers at the 60 ends of the narrow portions of the aforesaid intermediate strip for moving the cards from one trackway to the other; an endless chain in the lower rail with the opposite lengths thereof traveling in the trackways of said 65
- rail, advertising cards each having a pin projecting from the center thereof and connected to the endless chain, and means for moving said endless chain.
8. A car poster panel comprising upper 70 and lower rails presenting trackways, the upper rail consisting of spaced apart strips connected at their upper ends with the intermediate strip reduced in width at the opposite ends of the poster panel and the lower rail 75 consisting of parallel walls with the intermediate wall cut away below the aforesaid narrow portions of the intermediate strip of the upper rail, and guiding fingers at the ends of the narrow portions of the aforesaid 80 intermediate strip for moving the cards from one trackway to the other; an endless chain in the lower rail with the opposite lengths thereof traveling in the trackways of said rail, a frame carrying the advertising cards 85 having a pin projecting from the center thereof in engagement with the links of the endless chain, and a sprocket wheel and operating means therefor for operating the chain.
9. A car poster panel for advertising cards comprising upper and lower rails presenting trackways, the upper rail consisting of spaced apart strips connected at their upper ends with the intermediate strip reduced in width 95 at the opposite ends of the poster panel and the lower rail consisting of parallel walls with the intermediate wall cut away below the aforesaid narrow portions of the intermediate strip of the upper rail, and guiding fingers 100 at the ends of the narrow portions of said intermediate strip for moving the cards from one trackway of said rail to the other, a frame carrying the advertising card and having upwardly projecting tongues at the ends thereof, and a pin projecting from the center 105 of the lower edge of the frame; together with an endless chain in the lower rail with the opposite lengths thereof traveling in the trackways of said rail, the pins on the frames carrying the advertising cards engaging the links of said chain, sprocket wheels over which the endless chain travels, and means for turning said sprocket wheels.
